UNITED STATES PATENT OFFICE

2,372,621

VENTILATING FAN

Lee Barton Williams, Pittsburgh, Pa.

Application May 8, 1944, Serial No. 534,612

1 Claim. (Cl. 230—264)

This invention relates to motor-controlled fan construction, and more particularly to motor-controlled fans used primarily for ventilating purposes.

An important object of the invention is to provide a ventilating fan wherein all moving parts thereof are completely encased, providing a fan which will be absolutely safe against injury to persons moving in proximity to the fan.

Another important object of the invention is to provide a fan structure which will direct a volume of air over a large area in a sweeping motion, thereby accomplishing the same results as the well known oscillating rotary fan, with an exceptionally less number of working parts than used in rotary fan construction, and with considerably less power.

Still another object of the invention is to provide a fan which, because of the small number of working parts and principle of operation, will be exceptionally quiet and cheap to manufacture, as compared with rotary fans in common use.

With the foregoing and other objects in view which will appear as the description proceeds, the invention consists of certain novel details of construction and combinations of parts hereinafter more fully described and pointed out in the claim, it being understood that changes may be made in the construction and arrangement of parts without departing from the spirit of the invention as claimed.

Referring to the drawings:

Figure 1 is a plan view of a ventilating fan constructed in accordance with the invention, the cover plate of the motor housing of the fan, having been removed.

Figure 2 is a horizontal sectional view through the fan housing.

Figure 3 is a vertical sectional view taken at right angles to Fig. 2.

Figure 4 is a transverse sectional view taken on line 4—4 of Fig. 1.

Referring to the drawings in detail, the fan housing which is substantially triangular in formation and formed with a slightly curved forward edge, is indicated by the reference character 5, the front wall of the housing being closed by the foraminous material 6 which guards the front of the fan housing against injury to persons moving in proximity thereto.

At the rear of the fan housing, where the side walls 7 merge, are upper and lower bearings 8 in which the shaft 9 operates, the shaft 9 being of a length to extend through the top 10 of the housing.

The fan blade is indicated by the reference character 11 and is connected with the shaft 9 by means of the plates 12 which rest against the bearings 8, as clearly shown by Fig. 3 of the drawings.

This blade or fan member 11 is of a length to extend to a point in proximity to the inner surface of the foraminous material 6, the blade being cushioned at the end of its stroke, by means of the cushioning members 13 which are secured to the inner surfaces of the side walls 7.

Secured to the upper end of the shaft 9, is an arm 14 to which the link 15 is connected, the link 15 also having connection with the pulley 16 at 17.

The pulley 16 is formed with a groove to accommodate the V-shaped belt 18 that moves over the pulley 19 mounted on the shaft 20 of the motor 21.

It will of course be understood that the motor, pulley and mechanism, employed in operating the shaft 9, are mounted in the motor housing 22 which rests on the top of the fan housing, near the rear end of the fan housing. A removable cover 23 is provided on the motor housing, so that ready access may be had to repair or oil the motor.

The reference character 24 designates feet, on which the fan housing is supported.

It will of course be understood that the motor receives electric current through wires 25, and the wires may be plugged into the usual house circuit.

From the foregoing it will be seen that due to the construction shown and described, the motor will operate to rotate the pulley 16 that in turn operates the shaft 9, through the link 15 and arm 14. The movement of the shaft 9 is such as to oscillate the fan blade 11, swinging it back and forth throughout the entire width of the fan housing. As the fan blade moves toward one of the side walls of the housing, it will be obvious that air will be forced outwardly through the front wall with excessive force, to supply the necessary ventilation.

It might be further stated that the fan is exceptionally quiet, and the movements of the fan blade 11 are cushioned at their limits of movement by the cushioning members 13.

What is claimed is:

A motor-operated fan comprising a portable housing having a wide front wall constructed of foraminous material, and having side walls converging toward the front wall, upper and lower spaced bearings mounted within the housing at

the rear thereof, a vertical shaft mounted within the spaced bearings, one end of the shaft extending through the top of the casing, a motor housing mounted on the fan housing and into which the shaft extends, a crank arm secured to the shaft, a link pivotally connected with said crank arm, a pulley to which the link is eccentrically connected, a motor mounted in the motor housing, a belt adapted to transmit power to the pul-

ley from said motor, and an oscillating fan blade of a width slightly less than the side walls of the housing, secured to said shaft, and adapted to move toward alternate side walls of the housing, forcing air from the housing, and cushioning members on the side walls of the housing adapted to cushion the movement of said fan blade.

LEE BARTON WILLIAMS.
